UNITED STATES PATENT OFFICE.

HERBERT LISTER, OF MONTREAL, QUEBEC, CANADA.

HAIR COMB.

Application filed December 21, 1925. Serial No. 76,734.

The invention relates to a hair comb, as described in the present specification and illustrated in the accompanying drawings that form part of the same.

5 The invention consists essentially of the novel features of construction pointed out broadly and specifically in the claims for novelty following a description containing an explanation in detail of an acceptable 10 form of the invention.

The objects of the invention are to conserve the hair of the head by avoiding the daily thinning process pursued by the average person with the conventional comb,

15 whereby the strands of hair are dragged out by the roots being caught between the teeth due to the formation of the back therebetween; to furnish to the public a comb of a sanitary construction, in which the microbe

20 of a skin disease cannot lurk, as the comb at the base of the teeth may be flushed with ease; to produce this comb at a moderate cost to the purchaser and enable the manufacturer and dealer to enjoy a reasonable

25 profit; to accommodate the construction of the comb to the modern styles of hair dressing for women and to particularly meet the wants of men; and generally provide a strong hold for the teeth and at the same

30 time a clean base therefor as well as a smooth running surface during the operation of combing.

In the drawings, Figure 1 is a front elevation of the comb showing the longitudinal 35 running bar.

Figure 2 is a longitudinal sectional view on the line 2-2 in Figure 1.

Figure 3 is a fragmentary cross sectional view in agreement with Figure 2.

40 Figure 4 is a cross sectional view on the line 4-4 in Figure 1.

Figure 5 is a cross sectional view on the line 5-5 in Figure 1.

45 Figure 6 is a perspective view of the comb.

Figure 7 is a cross sectional view, showing the comb without the extension back.

Figure 8 is a perspective view showing the comb without the extension back.

50 Like numerals of reference indicate corresponding parts in the various figures.

Referring to the drawings, the back 11 of the comb extends into a running bar 14

from which the fine teeth 12 and coarse teeth 13 project thereby forming between 55 the teeth the rounded running surfaces 14, these surfaces engaging the head of the user and slipping along thereon without obstruction as the teeth separate the hairs of the head and these hairs pass over the curved bar without any strain whatsoever, in fact 60 said bar is actually a runner on the bed of hair parted by the teeth and not a single hair is caught at the base of the teeth, where usually in the well known type of comb 65 there is invariably a quantity of hair often a handful.

The comb as illustrated is the preferable 70 form of construction, though it must be understood that the essential feature is a running surface between the teeth extending around at least part way to the back.

In the use of the comb, there is no particular way that is required in the combing of the hair to enjoy the benefits arising from 75 the construction thereof as in vertical or flat combing the running surfaces will be equally efficient and bring forth the desired result of effecting a smooth road for the comb.

80 The manufacture may be carried out in much the same fashion as at present.

In Figure 7 the comb illustrated is more suitable for women and in this form of the invention the back of the comb is also the 85 running bar as indicated by the numeral 15 and the surfaces 16 between the teeth 17 continue the circle of the bar.

What I claim is:—

1. A hair comb, comprising a straight running bar, transversely circular in cross section and of identical diameter throughout, and a plurality of teeth having their inner ends in semi-arc construction and merging into said transversely circular running bar and projecting vertically therefrom and forming semicircular slideways between each tooth formed by the juncture of said teeth and transversely circular running bar. 90

2. A hair comb comprising a straight running bar forming a hand gripping member at the upper end portion and terminating at its lower portion into a transverse circular member and a plurality of fine and coarse teeth having their inner ends recessed 95 100 105

and shaped following the contour of said transverse circular member of the running bar and adapted to form part therewith and forming divisions and semicircular slideways between one another.

3. In a hair comb, a running bar of even diameter throughout and circular in cross section and having teeth projecting therefrom and tapering from either side of said

bar to thin central points and at their inner ends of substantially similar dimensions laterally to the diameter of said bar, the latter forming curved pathways transversely between the teeth.

Signed at Montreal, Canada, this 11th day 15 of December, 1925.

HERBERT LISTER.
